UNITED STATES PATENT OFFICE.

CHARLES E. VAN DYKE, OF HARLOWTON, MONTANA.

CATTLE-GUARD.

1,188,584.

Specification of Letters Patent. Patented June 27, 1916.

Application filed November 27, 1915. Serial No. 63,803.

To all whom it may concern:

Be it known that I, CHARLES E. VAN DYKE, a citizen of the United States, residing at Harlowton, in the county of Meagher and State of Montana, have invented certain new and useful Improvements in Cattle-Guards, of which the following is a specification, reference being had to the accompanying drawings.

10 This invention relates to certain improvements in cattle guards, and it is an object of the invention to provide a novel and improved device of this general character wherein cattle are effectively prevented from 15 following a railroad right-of-way.

Furthermore, it is an object of the invention to provide a cattle guard of this general character including side wings supported in such a manner as to permit an 20 elevation or depression of the intermediate portion of the guard without affecting the supporting members with which the wings 25 coact.

The invention consists in the details of 25 construction and in the combination and arrangement of the several parts of my improved cattle guard whereby certain important advantages are attained and the device is rendered simpler, less expensive and 30 otherwise more convenient and advantageous for use, all as will be hereinafter more fully set forth.

The novel features of the invention will be carefully defined in the appended claim.

35 In order that my invention may be the better understood, I will now proceed to describe the same with reference to the accompanying drawings, wherein—

Figure 1 is a view in top plan, with a 40 portion broken away, of a cattle guard constructed in accordance with an embodiment of my invention and in applied position; Fig. 2 is a vertical sectional view taken substantially on the line 2—2 of Fig. 1; Fig. 3 45 is a vertical sectional view taken substantially on the line 3—3 of Fig. 1.

As disclosed in the accompanying drawings, my improved cattle guard comprises a predetermined number of ties T on which 50 the rails R of a track-way are adapted to rest in a conventional manner, and each of said ties T at their ends intermediate the rails R have a corner inclined, as at 1, and

to which inclined faces the lower ends of the plates 2 and 3 are suitably anchored, said 55 plates extending upwardly a distance substantially equal to the height of the rails R.

The plates 2 are arranged at the ends of the tie and at substantially their longitudinal centers are provided with the reinforcing or strengthening ribs 4, the intermediate plate 3 being provided at a predetermined point intermediate each of its ends with the parallel related reinforcing or strengthening ribs 5. Each of the plates 2 and 3 has 60 its upper marginal portion provided with the strengthening rib 6 which has formed in continuity therewith the depending flange 7 which serves to prevent the hoofs of the cattle from being injured. The ends of the 70 ties are tied or connected by the elongated strip 8 with which the lower portion of a wing W is attached. Each of the wings W is substantially in the form in plan of an inverted V and comprises the converging 75 side strips 9 connected by the parallel related spaced strips 10 also arranged in substantial parallelism with the rails R. The opening 11 afforded by the upper strip 10 and the point of the wing has loosely directed therethrough a supporting post P and the remaining strips 10 of the wing are secured to the post P through the medium of the wires 12 whereby it will be perceived that the flexibility of the wires 12 will permit a raising or lowering of the ties T without materially affecting the support afforded by the post P. It is to be noted that the extremities of the members 10 are secured to the post P and the intermediate portions 80 thereof are looped about the transverse strips 10, and free to move longitudinally relative to the strips 10.

From the foregoing description, it is thought to be obvious that a cattle guard 95 constructed in accordance with my invention is of an extremely simple and comparatively inexpensive nature and is particularly well adapted for use by reason of the convenience and facility with which it may be assembled, 100 and it will also be obvious that my invention is susceptible of some change and modification without material departure from the principles and spirit thereof and for this reason I do not wish to be understood as 105 limiting myself to the precise arrangement

and formation of the several parts herein shown in carrying out my invention in practice.

I claim:

- 5 In combination with a cattle guard, end guards coacting therewith, each of said end guards comprising a plurality of transversely disposed spaced strips, a fixed supporting post for each of the end guards and
- 10 freely disposed therethrough, and flexible members having their extremities secured to

the post, the intermediate portions of the member being looped about the transverse strips and free to move longitudinally relative thereto.

15

In testimony whereof I hereunto affix my signature in the presence of two witnesses.

CHARLES E. VAN DYKE.

Witnesses:

S. T. JOHNSON,
J. WHEELER FREEMAN.
